UNITED STATES PATENT OFFICE

104,041

DESIGN FOR A GOLF PUTTER HEAD

Walter McCulla, East Falls, Pa.

Application March 16, 1936, Serial No. 61,666

Term of patent 3½ years

To all whom it may concern:

Be it known that I, Walter McCulla, a citizen of the United States, residing at East Falls, in the County of Philadelphia and State of Pennsylvania, have invented a new, original, and ornamental Design for a Golf Putter Head, of which the following is a specification, reference being had to the accompanying drawing, forming part thereof.

Figure 1 is a view in front elevation of a golf putter head, showing my new design.

Figure 2 is a view in side elevation thereof. A characteristic feature of the design is the merging of the substantially flat half-moon above the middle of the article, into the lower concave half-moon, which produces a faceted, jewel-like cooperation of light reflecting surfaces.

I claim:—

The ornamental design for a golf putter head as shown and described.

WALTER McCULLA.
